(57) **CLAIM**

The ornamental design for stockings, as shown and described.

DESCRIPTION

The file of this patent contains at least one drawing executed in color. Copies of this patent with color drawings will be provided by the Office upon request and payment of the necessary fee.

FIG. 1 is a photograph of a front view of a first embodiment of a stocking showing my new design;

FIG. 2 is a photograph of a right side view of the stocking shown in FIG. 1;

FIG. 3 is a photograph of a rear view of the stocking shown in FIG. 1;

FIG. 4 is a photograph of a left side view of the stocking shown in FIG. 1;

FIG. 5 is a photograph of a bottom view of the stocking shown in FIG. 1;

FIG. 6 is a photograph of a front view of a second embodiment of a stocking showing my new design;

FIG. 7 is a photograph of a right side view of the stocking shown in FIG. 6;

FIG. 8 is a photograph of a rear view of the stocking shown in FIG. 6;

FIG. 9 is a photograph of a left side view of the stocking shown in FIG. 6;

FIG. 10 is a photograph of a bottom view of the stocking shown in FIG. 6;

FIG. 11 is a photograph of a front of a third embodiment of a stocking showing my new design;

FIG. 12 is a photograph of a right side view of the stocking shown in FIG. 11;

FIG. 13 is a photograph of a rear view of the stocking shown in FIG. 11;

FIG. 14 is a photograph of a left side view of the stocking shown in FIG. 11;

FIG. 15 is a photograph of a bottom view of the stocking shown in FIG. 11;

FIG. 16 is a photograph of a front of a fourth embodiment of a stocking showing my new design;

FIG. 17 is a photograph of a right side view of the stocking shown in FIG. 16;

FIG. 18 is a photograph of a rear view of the stocking shown in FIG. 16;

FIG. 19 is a photograph of a left side view of the stocking shown in FIG. 16; and,

FIG. 20 is a photograph of a bottom view of the stocking shown in FIG. 16.
